M. P. HOLMES

CONTROLLING MECHANISM

Filed June 12, 1924

Patented Oct. 25, 1927.

1,646,694

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

CONTROLLING MECHANISM.

Application filed June 12, 1924. Serial No. 719,691.

My invention relates to controlling mechanisms.

An object of my invention is to provide an improved controlling mechanism. Another object of my invention is to provide an improved clutch controlling mechanism. A further object of my invention is to provide an improved controlling mechanism whereby a plurality of clutches may be selectively controlled by means of a common operating element. A still further object of my invention is to provide an improved clutch controlling mechanism especially adapted to use in a mining machine of the low vein type whereby the feed operating member may be driven selectively at fast or slow speeds and having a common operating element of improved form for simultaneously controlling the clutches. These and other objects and advantages of my invention will, however, hereinafter more fully appear.

In the accompanying drawings I have shown for purposes of illustration one form which my invention may assume in practice.

In these drawings,—

Fig. 1 is a plan view of a portion of the feed end of a mining machine in which my improved controlling mechanism is incorporated, the view being partially in section and broken away to facilitate illustration.

Fig. 2 is a transverse vertical sectional view taken substantially on line 2—2 of Fig. 1.

Figs. 3 and 4 are detailed sectional views, partially in elevation, of my improved controlling mechanism.

Fig. 5 is a transverse vertical sectional view taken substantially on line 5—5 of Fig. 4.

In this illustrative form of my invention I have shown my controlling mechanism, which is an improvement over that disclosed in my copending application Ser. No. 705,089, filed April 8, 1924, applied to a self-propelled mining machine of the same general type described and claimed in my copending application Ser. No. 619,839, filed Feb. 19, 1923, which comprises a frame 1 on which a feed operating member 2 (indicated in dotted lines in Fig. 1) is suitably journaled, and which is adapted to cooperate with a flexible feeding member in the

form of a chain (not shown), in a well known manner to propel the machine on its own bottom along the mine bottom. The feed operating member 2 is adapted to be driven at fast or slow speeds in opposite directions through suitable frictional controlling devices, generally designated 3 and 4, respectively, these devices being adapted to be selectively placed in operation by means of improved controlling mechanism, thereby connecting the feed operating member 2 with the fast or slow feed.

In describing my improved controlling mechanism it will be noted that the frictional controlling devices 3 and 4 are adapted to be selectively placed in operation by means of suitable clutch shipper members 5 and 6 of U-shaped form, pivoted on vertical axes as at 7 and 8 and which are provided at their inner ends with suitable rollers 9 and 10 adapted to engage disk-like outer surfaces 11 and 12 of the controlling devices 3 and 4.

Moreover, it will be noted that the shipper members 5 and 6 are provided with extensions 13 and 14 extending radially from the pivots 7 and 8 into lateral slots or apertures 15 and 16 formed in ring-like portions 17 and 18 suitably carried in a circular bore 19 formed in the machine frame 1. These extensions 13 and 14 are provided with rectangular shaped portions 20 and 21 having arcuate engaging surfaces which register with slots or grooves 22 and 23 formed in parallel slidable rods 24 and 25 suitably guided in the machine frame at their opposite ends, as at 26. These rods are grooved or cut away at 27 and 28 to permit longitudinal relative movement therebetween and are provided with semi-circular portions 29 and 30 which are in turn provided with threads of opposite inclination,

with which an annular nut member 31 cooperates. This nut 31 is comprised of semi-circular portions 32 and 33 which are each internally threaded, as at 34, with right and left hand threads. It will be noted that an operating handle 35 is secured to the portions 32 and 33 of the nut 31 by means of bolts 36 and 37, respectively, and is provided with an elongated cylindrical portion 38 which overlaps the semi-circular portions of the nut, thereby preventing separation of the same and forming a rigid unit. Dis-

posed between the inner end of the nut 31 and a shoulder 39 formed on a portion of the machine frame and encircling the portions 29 and 30 of the rods is a sleeve or 5 spacer member 40.

In the use of my improved controlling mechanism, it will be noted that when the operating handle 35 is rotated the internally threaded nut member 31, engaging the 10 threads formed on the cylindrical portions 29 and 30 or the rods 24 and 25, will react against the shoulder 39 of the frame through the sleeve member 40 and will thus cause the rods to simultaneously move in 15 opposite directions, thereby swinging the shipper members 5 and 6 about their pivots 7 and 8 in opposite directions and causing one of the frictional controlling members to be released while the other is applied, 20 consequently preventing the application of both the clutches, and consequently the fast or slow feeds, simultaneously.

As a result of my improved construction, it will be noted that I have provided an 25 improved controlling mechanism for selectively operating a plurality of clutches and which has a common operating element of improved form which is readily accessible from the exterior of the machine frame for 30 assembly and adjustment. It will further be noted that I have provided an improved controlling mechanism of exceedingly simple, rigid, and compact construction, which may be applied to a mining machine of 35 standard form with a minimum of change and expense.

It should be understood that this application is directed to an improvement over the structure disclosed in my copending application, Serial No. 705,089, in which earlier filed application I present claims to subject matter common to that and the present application.

While I have in this application specifically described one form which my invention may assume in practice, it will be understood that this form of the same is shown for purposes of illustration and that the invention may be modified and embodied in 50 various other forms without departing from its spirit or the scope of the appended claims.

What I claim as new and desire to secure by Letters Patent is:

55 1. In a controlling mechanism, a plurality of clutch elements, and means for selectively applying said clutch elements including rods having threaded portions formed thereon, a plural part split nut cooperating with said portions, and an operating element for said nut having a cylindrical portion formed thereon adapted to encircle and retain the parts of said nut in operative position.

60 2. In a controlling mechanism, a plurality

of clutch elements, and means for selectively applying said clutch elements including parallel oppositely movable rods having threaded portions formed thereon, a plural part split nut cooperating with said portions, and an operating element having a cylindrical portion formed thereon adapted to encircle and retain the parts of said nut in operative position. 70

3. In a controlling mechanism, a plurality of clutch elements, shipper members cooperating therewith, rods cooperating with said shipper members having threads of opposite inclination formed thereon, a plural part split nut cooperating with said threads, and an operating element having a cylindrical portion formed thereon adapted to encircle and retain the parts of said nut in operative position. 75 80

4. In a controlling mechanism, a plurality of frictional controlling devices, and means adapted to alternatively operate said devices including a nut comprised of a pair of separate semi-circular internally threaded portions, and an operating member secured to said portions encircling and holding them together. 85 90

5. In a controlling mechanism, a plurality of frictional controlling devices, and means adapted to selectively operate said devices including a nut comprised of separate semi-circular internally threaded portions, and an operating member secured to said portions and having a cylindrical portion overlapping said nut portions and holding them together. 95 100

6. In a controlling mechanism, a plurality of frictional controlling devices, and means adapted to selectively operate said devices including shipper members, parallel rods cooperating therewith having threaded portions of opposite inclination formed thereon, a plural part split nut cooperating with said threaded portions, and means to encircle and retain the parts of said nut in operative position having an operating portion formed thereon. 105 110

7. In a mining machine, a feed mechanism including a plurality of friction clutches, and means for selectively applying said clutches including parallel relatively movable threaded slotted rods, a plural part split nut, and a common operating element for said clutches adapted to encircle and retain the parts of said nut in operative position. 115 120

8. In a mining machine, a feed mechanism including a plurality of clutches, shipper mechanisms cooperating therewith having extensions formed thereon, parallel oppositely movable threaded rods having notches cooperating with said extensions, a plural part split nut cooperating with said threaded rods, and a common operating element for said nut adapted to encircle and retain 125 130

the parts of the latter in operative position.

9. In a controlling mechanism, a plurality of operating elements, and actuating means for said operating elements comprising oppositely threaded members operatively connected one to each of said operating elements, a plural part nut each of whose parts

comprises thread means adapted to cooperate with the threads of each of said threaded members, and means common for holding assembled the separate parts of said nut and for rotating the latter. ¹⁰

In testimony whereof I affix my signature.

MORRIS P. HOLMES.
